PUMP

Frank E. Stelzer, Lynbrook, N. Y.

Application November 5, 1935, Serial No. 48,411

10 Claims. (Cl. 230—108)

This invention relates to centrifugal pumps and has for its general object the provision of rotary pumps of this type which may be employed to transfer a single fluid; to mix fluids of different characteristics; or to act upon a gaseous fluid by the rotation and ejection of a body of liquid, in order to create a vacuum or to effect the compression of the gaseous fluid. The invention also contemplates the provision of certain installations by means of which the pump may be made to effect the purposes set forth.

A more particular object of the invention is to provide in such pumps impellers of novel and improved constructions designed to centrifugally project the denser one of the fluids being pumped through restricted orifices so as to draw the other fluid along with it in much the same manner as that of an ordinary aspirating pump, injector or the like. It is also an object of the invention to provide novel pump casings adapted for the reception of such impellers and for the control of the flow of the fluids entering and leaving the pump.

Other objects include the provision of certain accessory devices rendering the several pump embodiments adaptable to a variety of uses. These include certain novel casing, tank, and conduit arrangements which constitute the preferred examples of the reduction of my invention to practice which are illustrated and described herein. These illustrative examples comprise installations for the operation of vacuum steam heating systems, steam condensing pumps, self-priming suction pumps, fluid mixers, sewage ejection systems, air compressors, etc.

Further objects and features of novelty will be apparent from the following specification when read in connection with the accompanying drawings, in which

40 Figure 1 is a vertical transverse sectional view of a pump unit embodying the principles of my invention, the line of section being substantially that indicated at 1—1 in Figure 2, but passing between the blades or vanes of the impeller for the sake of clearness of illustration;

Figure 2 is a vertical sectional view of the pump taken on a plane perpendicular to that of Figure 1 as indicated by the line 2—2 in that figure;

Figure 3 is a partial sectional view taken substantially on line 3—3 of Figure 2;

Figure 4 is a partial sectional view taken substantially on line 4—4 of Figure 2;

Figure 5 is a partial sectional view showing a modification in the air intake portion of the casing;

Figure 6 is a sectional view of a modified form of impeller adapted for use in a combined liquid transfer and suction pump;

Figure 7 is an end elevation on a reduced scale of a pump installation embodying the principles of my invention and adapted for use in connection with a vacuum steam heating system; two identical pumps capable of being used in connection with a double tank provided with means for separating and controlling the flow of the feed water and condensate;

Figure 8 is a vertical transverse sectional view of one of the pump units, the tank being shown in elevation rearwardly of the pump;

Figure 9 is a view in elevation of the tank, a portion thereof being shown in section as taken on line 9—9 of Figure 14, this view also indicating diagrammatically the automatic controlling means for the pump motor;

Figure 10 is a view in vertical section taken through the pump and one-half of the double tank, substantially on lines 10—10 of Figures 8 and 9, and indicating the construction of the alternative single tank to be used with only one pump;

Figure 11 is a partial vertical sectional view taken through the tank line 11—11 of Figure 9;

Figures 12 and 13 are similar views taken on lines 12—12 and 13—13 respectively of the same figure;

Figures 14 and 15 are partial views in horizontal section taken through the tank on lines 14—14 and 15—15 respectively of Figure 9;

Figure 16 is a view of the tank in vertical section taken on line 16—16 of Figure 14;

Figure 17 is a view in vertical section of an embodiment of my invention adapted for use as a fluid mixer, a self-priming centrifugal pump, or the like;

Figure 18 is a view partly in elevation and partly in vertical section of an installation adapted for use as an air pump in a variety of capacities, such as, for example, in connection with the sewage ejector illustrated in elevation in Figure 19;

Figures 20 and 21 are longitudinal sectional views illustrating certain arrangements of single suction impellers for use in existing pump casings or in especially designed installations.

In the first five figures of the drawings there is illustrated a double suction pump which constitutes a preferred embodiment of my invention and which may be employed without substantial alteration in many of the installations described and suggested herein. The pump casing indi-

cated generally by the reference character 10 is preferably divided horizontally into an upper section 11 and a lower section 12, suitable sealed connections being made between the connecting flanges at 13. Any suitably formed base or pedestal portion may be provided as at 14. The two sections of the casing 10 are shaped to provide a central impeller chamber 15 which is of a volute configuration and preferably is formed with its side walls converging toward the periphery thereof so as to provide a sort of Venturi effect in cooperation with the aspiratory impeller which will presently be described. Spaced laterally from the centrally located impeller chamber 15 the casing 10 is formed with annular enlargements 16 with which cooperate certain sealing rings and portions of the impeller to provide inlet chambers for the air or other aspirated fluid. Still further remote from the center of the pump are provided the enlargements 17 which, together with certain cooperating parts of the structure provide inlet chambers for the water or other liquid employed as the propelling or aspirating medium.

The rotary aspiratory impeller employed in this embodiment is indicated generally by the reference character 20 and comprises an elongated hub portion 21 secured to the drive shaft 22 which is adapted to be operatively connected with a suitable motor. Preferably bearing sleeves 23 are provided at the ends of the impeller and form substantially extensions of the hub thereof. Suitable packed bearings or stuffing boxes 24 surround these sleeves and provide sealing means between the pump casing and the rotary portions of the pump. Centrally of the pump the hub 21 of the impeller is provided with the streamlined enlargement 26 upon which are formed the curved radially extending vanes or blades 27, these vanes 27 being bounded laterally by the shrouds 28, forming the buckets of the impeller. The shrouds 28 are extended axially of the pump to form the tubular walls 29 of the impeller. These walls 29 are provided with flanges or seats for the sealing and bearing rings 30 which are also seated in suitable grooves formed in the casing and serve to separate the air inlet chambers indicated at 16 from the impeller chamber 15 of the pump. Similar sealing and bearing rings 32 are provided between the air inlet chamber 16 and the water inlet chambers 17, these rings being seated appropriately in the casing wall and also provided with a seat 33 forming a bearing for the impeller 20.

The radially enlarged central portion of the impeller is provided with the spaced partitions 35 which intersect the vanes 27 and are continued axially to form the tubular portion 36 which eventually merges with the outer tubular portion 29 of the impeller adjacent the end seat or shoulder 33. It will be noted that these tubular portions 36 of the partitions 35 divide the end portions of the impeller into annular air and water inlet conduits designated respectively by the reference numerals 39 and 40, the conduit 39 being placed in communication with the air inlet chamber 16 of the casing as by means of the openings 41 and the annular conduit 40 communicating with the water inlet chamber 17 through the center of the outer sealing ring 32 as at 42. It will be further noted that the radial portions of the partitions 35 extend only a short distance outwardly between the shrouds 28 terminating at the point 45 to form with the vanes 27 a series of smaller inner buckets the peripheral openings of which may be considered as propelling

fluid jets. It will be readily seen that there is thus provided between the mouths of the impelling jets at 45 and the outer peripheral margin 46 of the impeller 20 a mixing chamber 48 wherein in the propelling fluid from the "nozzles" defined by the partitions 35 mix with and aspirate the propelled fluid and draw it through the laterally outwardly disposed series of buckets of the impeller between the shrouds 28 and the partitions 35. Thus, by combining the aspirating and centrifugal effects, both fluids may be effectively mixed and propelled through the volute chamber 15 and thence outwardly through the common outlet 50 provided, in this instance, in the upper casing portion 11.

An intake connection 52 for the water or other propelling fluid is provided in this case in the lower casing portion 12 and is divided as at 53 into two laterally extending passageways 54 which provide communication with the water inlet chamber 17. An air or other aspirated fluid inlet connection 55 is similarly divided as at 56 to provide the lateral passageways 57 each leading to one of the air inlet or aspirated fluid chambers 16. By-pass passageways 58 are provided in the casing between the chambers 16 and 17 and are adapted to be controlled by suitable valves or plugs suggested at 59. In Figure 5 there is illustrated an alternative form of air intake which may be employed in some installations in which the air is introduced through a lateral opening 60 and is conducted into the air inlet chambers 16', which lie between the water inlet chambers 17' and the central impeller volute chamber 15'.

In cases where it may be desired to aspirate different fluids through the two sides of the pump, two of the air inlets such as indicated at 60 in Figure 5 may be provided, one on either side of the casing and a partition indicated in dotted lines at 62 may be formed in order to separate the two inlet chambers 16' on either side of the pump. In some installations this arrangement may be desirable when it is necessary to pump air or vapor on one side of the casing and steam condensate, for example, on the other. A diffusion vane indicated at 65 in Figure 2 may also be inserted in the outlet 50 of the chamber 15.

The stuffing boxes 24 provided in the casing for the accommodation of the rotary drive shaft 22 are connected with the volute chamber 15 by means of the small pipes 66 to provide a water seal. The stuffing boxes or bearings 24 could also be suitably connected with external sources to provide the desired vacuum or water seal.

The operation of the pump in its various suggested uses will now be indicated. In order to compress air or other gaseous fluids, a circulating body of water or other liquid may be maintained in the pump and a suitable return system which will preferably include a separating tank. This body of denser fluid being thrown through the inner series of buckets or "nozzles" at 45 will effectively aspirate the air through the outer buckets of the impeller between the shrouds 28 and partitions 35, through the mixing chamber portions 48 of the outer buckets, the volute chamber 15, and thence through the outlet 50 into a suitable separatory chamber and into a suitable container for the compressed fluid. Alternatively, the pump may be employed as a mixing device for different fluids, both being liquid or one of them liquid and the other gaseous as in carbonating processes, the fluids

being admitted separately into the inlet chambers 16 and 17 and then mixed and ejected by the impeller as described. The use of the pump as a steam condensing pump will be readily understood, the condensing water being passed through the propelling or aspirating system 52, 54, 17, 40, 45, 48, etc. and the exhaust steam being admitted through the propelled fluid system 55, 57, 16, 39, 48, etc. Vacuums may be produced by connecting the air inlet 55 with the space to be evacuated and circulating a body of water or other aspirating medium through the proper channels. The pump, of course, may be employed in various other installations, for example, for agitating different kinds of liquids or washing and cooling gases.

In Figure 6 of the drawings there is illustrated a modified type of impeller which is adapted to perform the double duty of pumping a single fluid through one portion of a suitable casing and propelling two fluids in aspirating relation in another portion of the casing. The aspirating side of the impeller is substantially the same as one side of the double suction impeller illustrated in the first five figures of drawing. The impeller designated generally by the reference numeral 70 is provided with a central bore through which a drive shaft 71 is adapted to pass, suitable keys being provided for rigidly mounting the impeller on the drive shaft. Upon the left hand side of the impeller there is provided an ordinary centrifugal rotor portion 72 having vanes 73 bounded by the outer shroud 74 and the inner shroud or partition 75, the buckets 35 bounded by the vanes 73 and the shrouds 74 and 75 being curved along with these members to provide an axial center inlet shown at 77. A guide ring or flange 78 may be provided on the inner wall or partition 75 to interlock with a suitable groove in the casing, or in the diaphragm sealing ring 79.

The right hand portion 80 of the impeller is provided with the blades or vanes 81 bounded by the outer shroud 82 which is quite similar in configuration to one of the shrouds 29 of the previously described embodiment having portions 83 and 84 shaped to cooperate with sealing and bearing rings just as in the other embodiment. A partition 85 divides the buckets of this portion of the impeller into two parts, an inner series 87 for the impelling fluid which passes axially through the inner annular passage 88 and the portion 89 for the aspirated fluid which passes through the conduits 90 which are in communication through the holes 91 with one of the intake chambers of the pump. This embodiment finds probably its greatest utilization in connection with vacuum steam heating systems, one of which comprises an important feature of the present invention, and will be described in considerable detail herein.

In Figure 20 there is illustrated an embodiment of the double impeller arrangement which may be employed in certain existing pump castings or in especially designed housing. In this arrangement the single suction pump impeller portion 80' is carried by the drive shaft 71' and is spaced any desired distance along the shaft from the separately formed centrifugal pump impeller portion 70'. These separately formed impeller sections are substantially identical with their corresponding integrally formed embodiments shown in Figure 6 and the various elements thereof will be given the same reference characters.

In Figure 21 of the drawings the single suction impeller 80'' is shown alone on its drive shaft 71'' and is provided with the same vanes, passageways and apertures which are shown and described in connection with the preceding embodiments. This impeller may be employed for the same purposes described in connection with Figures 1-5 of the drawings but wherein a pump of less capacity is desired.

The pumping installation forming a part of 10 a vacuum steam heating system and comprising another embodiment of the principles of my invention is illustrated in Figures 7-16 inclusive of the drawings. In Figure 7, which is a view in elevation of a double pumping arrangement, the 15 two pumps are indicated at A and B and a double condensate receiving and separating tank is indicated at C. For systems of smaller capacities a single unit may be employed comprising one of the pumps—say pump A,—and only half of the 20 tank C, the double tank C being exactly symmetrical upon either side of the center line x—x. In this case, the left hand side of the tank will be provided with a solid wall along the plane of the line x—x, and certain minor alterations and 25 adjustments being effected in the condensate and valve connections, as will be hereinafter described. In connection with most of the figures of drawings, only one side of the double arrangement shown in Figure 7 will be described, it being 30 understood that this much of the device can be employed in smaller systems, and in order to double the capacity of the pumping arrangement the device has merely to be duplicated upon the opposite side of the lines x—x appearing in these 35 figures.

The pump unit employed in these connections is clearly illustrated in Figures 8 and 10 of the drawings, both the pump A and the tank C being mounted upon a base plate 100 and certain chambers of the pump utilizing a portion of his plate 100 as a bottom wall, the vertical walls of the tank proper being sealed thereagainst by suitable gaskets or other water and air-tight devices. The casing of the pump A is preferably formed in two sections, an upper section 101 and a lower section 102 being joined by suitable connecting and packing means, stuffing boxes 103 being provided for the impeller drive shaft 104 passing through the pump. The pump casing is also provided with spaced anti-friction bearings 105 for the drive shaft carried by the brackets 106, these bearings comprising the ball-bearing assemblies 107, and associated sleeves and packings. The shaft is adapted to be driven by a suitable motor, a portion of which is indicated at 108 in Figure 9, in which figure there is also diagrammatically shown certain automatic controls for the motor which will be described at the proper place hereinafter.

The impeller in this pump is of exactly the same construction as that designated 70 in Figure 6 of the drawings and the same reference characters will be used to indicate the various parts in these figures. The right hand aspiratory section 80 of the impeller is employed to withdraw the condensate and air from a portion of the receiving tank C by utilization of a body of priming or propelling water which is always maintained at a substantially constant level in a certain portion of the tank and in the pump casing, this level being indicated by the line y—y in certain figures of the drawings. The priming or propelling water chamber of the pump casing is indicated at 110 of the drawings and corresponds to the similar chamber 17 in the earlier described figures. 75

This priming water intake chamber 110 is connected with the tank by means of the conduit 111 which may be placed in communication with the tank opening 112 by means of the valve 113. 5 The condensate chamber 115 is provided in the casing adjacent the priming water chamber 110 and separated therefrom by means of the ring 116 which provides a sealing means for the portion 84 of the propeller 70. The condensate or 10 propelled fluid chamber 115 is placed in communication with the tank C by means of a suitable conduit 119 communicating with the opening 120 in the tank. Another bearing ring 122 is provided for sealing off the condensate intake chamber 15 115 from the volute impeller chamber 125 and cooperates with the bearing flange 83 of the impeller. The annular passageway 88 surrounding the impeller shaft 104 provides means for transmitting the priming water from the intake chamber 110 to the inner buckets 87 of the impeller. The condensate fluids pass from the intake chamber 115 through the openings 91 and thence through the annular passageway 90 into the outer bucket portions 89.

20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

level to prime the pump; to provide a reservoir for the boiler feed water; to provide means for separating the air and vapors from the condensate fluid and priming water mixtures; and to provide certain conduits for the admission and delivery of these various supplies of fluid. Communications are provided between these various compartments where necessary and baffles and valves are arranged in the tank to maintain the required levels in certain of the compartments and to prevent siphoning of the residual fluids, all as will be hereinafter described in detail.

The tank C is provided with an inlet opening 150 near the bottom thereof which is connected through the check valve 151 and the screen 152 with the return main of the heating system, a portion of which is shown at 153 in Figure 8. From the opening 150 the condensate liquid from the system passes through the low horizontal passageway 155 and from thence it rises upwardly in the vertical compartment 156 to the level $y-y$, whereupon it may flow in two directions, namely, forwardly over the baffle wall 158 and thence downwardly through the spring pressed check valve 159 into the compartment 160 and also laterally over the baffle wall 161 through the opening 162 into the vertical compartment 163. The condensate under the proper running conditions of the pump is withdrawn from the chamber 160 through the outlet opening 120 and into the condensate chamber 115 of the pump as already described.

The necessary supply of priming water is retained in the compartment 165 of the tank, this chamber or compartment 165 having the forwardly disposed downwardly extending leg 166 from which the priming water is taken through the opening 112, valve 113, and conduit 111 to the priming water inlet chamber 110 of the pump. The priming water chamber 165 has a horizontally extending portion 167 which overlies both of the condensate compartments 156 and 160. The mixed priming water and condensate return through the conduit 128 from the right hand outlet of the pump A passing through the elbow 168 back into the upper portion of the priming water chamber 165 through the opening 169. Suitable air vents may be provided in the top of the priming water chamber 165 to permit the escape of air.

Upon the left hand side of the tank there is provided a boiler feed water compartment 170 which obtains its supply of water from the overflow of the priming water chamber 165 through the openings 171. The feed water chamber 170 is provided with a forward downwardly extending leg 172 from which the outlet 132 leads through the valve 134 into the inlet chamber 136 of the left hand side of the pump A. The feed water is propelled through the outlet 138 into the opening 140 in the cupola or dome 130 and thence downwardly through the spring controlled check valve 174 into the upper horizontal conduit or passageway 175 in the tank, from whence it flows through the outlet 176 into the piping leading to the boiler. The feed water chamber is provided with an air vent 177 and the lower leg 172 of this chamber is provided with communication with the supplementary condensate reservoir 163 by means of the opening 178 in the partition 179 controlled by the valve 180. The valve stem 181 extends through the stuffing box 182 in the front wall of the tank and is provided with an operating handle 183.

An atmospheric relief line 185 serves to con-

nect the upper portion of the condensate chamber 156 at a point above the check valve 159 with the highest point of one of the inlet chambers of the pump as, for example, the condensate fluid inlet chamber 115 as indicated in Figures 10 and 13 of the drawings. This is for the purpose of breaking an undesired siphon effect which will be described in connection with the operation of the pumping installation.

10 In Figure 9 of the drawings there is diagrammatically illustrated certain instrumentalities by which automatic control of the pump is insured. A portion of the motor which drives the pump is indicated at 108. A portion of the return main of the vacuum heating system is shown at 189 and to this main is applied a vacuum indicator and vacuum controlled electric switch 190 of any conventional type. A float 192 is disposed in the boiler fed water chamber and is adapted to control the switch 193. The current main which supplies the motor 108 is indicated at 195 and may be provided with a master switch 196. The vacuum control switch 190 and the float control switch 193 are each arranged in series with the motor 188 so as to individually control the operation thereof. The switches 190 and 193 may be thrown into and out of service by the manually operated switches 198 and 199. Another manually operated switch 200 may be employed to energize the motor 108 regardless of the conditions affecting the automatic switches 190 and 193.

Under normal operation of the system, the switches 198 and 199 are closed and the switch 200 is open, thus establishing the automatic control of the pump driving motor 188. When the vacuum in the return pipes of the heating system 189 falls below the desired point, the automatic switch 190 is actuated and the motor 188 starts the pump in operation. Then if there is any liquid condensate in the tank it is withdrawn by the aspirating action of the priming water and both are returned to the priming water compartment 165, the excess water spilling over through the openings 171 into the feed water compartment 170 from which it is supplied to the left hand boiler feed pump side of the pump A through the proper passageways in the dome 130 and the outlet conduit 175 in the upper portion of the tank. If there is no liquid condensate in the system, or after the liquid condensate has been thus withdrawn, the suction side 80 of the pump withdraws air from the system and produces the desired degree of vacuum whereupon the vacuum regulator stops the motor and the pump. The air that is withdrawn from the system escapes through the vents in the priming water and feed water tanks.

On the other hand, when the water level in the feed water compartment 170 rises beyond the desired point, the float valve 193 is actuated and the pump is started so as to deliver this excess feed water to the boiler. If, during this phase of the operation, the vacuum in the return system is already sufficient, suitable vacuum relief valves disposed in the return system will maintain the vacuum at the proper degree.

In starting up the system after a period of idleness during which the heating system has become partly filled with accumulated condensate, 70 the by-pass valve 180 is opened, connecting the feed water compartment 170 with the supplemental condensate compartment 163 and the main switches for automatic regulation are closed, the resulting high level in the feed water compartment causing the float switch to start the

pump. The condensate is thus permitted to flow directly through the valve controlled opening 178 into the feed water compartment and thence to the opening 182 into the left hand or feed water side of the pump and thence to the boiler. When the condensate in the heating system has been removed sufficiently to cause the level in the boiler feed water compartment of the tank to attain the proper point, the float control valve 193 will open. This method of starting the system has a great advantage since it is quicker to empty the return conduits of condensate in this manner than to attempt to create a vacuum in the system first. When the excess accumulation of condensate has been returned to the boiler, the vacuum operated switch 190 is then thrown into operation by manipulation of the switch 198 and the by-pass valve 180 is closed. The pump will then exhaust the air from the heating system and produce the necessary partial vacuum and the unit 20 will function automatically, as already described, returning the water to the boiler when necessary and maintaining the vacuum in the system between fixed limits.

The system, when desired, can be operated without vacuum as a gravity return system under atmospheric pressure. For example, during night operation when fires have been banked, the vacuum control is cut out, but the float control is left in operation and the valve 180 is opened. During this period the valve 113 is closed and the condensate is returned to the boiler through the left hand or feed water side of the pump. When a sufficient amount of condensate fills the system the float valve operates the pump until the water has fallen to the proper level when the pump is cut off.

Since this automatic operation does not occur very frequently during this period when the fires are banked and very little steam generated, there would be danger that the cooling of the system would produce a back vacuum which would draw off, not only the condensate, but the priming water for the left side of the pump. The check valve 151 should take care of this situation but additional precautions are necessary in case of leakage of this check valve. As already indicated, the height of the wall or baffle 158 is determined according to the necessary priming water level and similarly the height of the wall 161 is so determined. A quantity of water is thus always trapped within the compartments 160 and 163 no matter how the pump is employed. The atmosphere relief line 185 effectively prevents the siphoning off of the necessary priming water, especially in cases where a back vacuum may occur on either side of the system and in the event that the check valve 159 and 151 should leak. Should such leakage occur through any or all of the check valves the water can only flow back into the system to the level of the relief pipe 185 where atmospheric air from the chamber 165 would flow back through the conduit 128 through the impeller passages 89, 90 and 91 and into the condensate intake chamber 115 of the pump to which the relief line 185 is connected. Thus the priming water supply is trapped and can only be drawn off by opening a suitable drain (not shown) in the chamber 165.

Although the various operations of the system 70 have been described in connection with the pump A only, it will be readily understood that the operation is very similar when both pumps A and B are provided, the apparatus being duplicated on each side of the installation as indicated in Fig- 75

ure 7 of the drawings. When both sides of the apparatus are in operation the valves 159 and 174 will open and close automatically according to whether or not there is enough condensate to keep them both in operation; in any case, the valves closing on the side of the pump that is not receiving condensate. When only the pump on the right hand side of the center line $x-x$ is operating, then the valve 174 on the left will close 10 against the boiler pressure and the left hand valve 159 will close against the vacuum. This feature permits making repairs on either pump unit while the other is operated; the valves 113 and 134 being closed during these operations. By 15 locating the high and low water levels in the priming water compartment 165 and the boiler feed water compartment 170 so that enough head on the pump suction is obtained, condensate of any temperature may be pumped.

20 Numerous advantages of the vacuum heating system pumping arrangement which has been described will be apparent. With this type of pump a high degree of exhaustion can be obtained and this more rapidly than in prior constructions. Greater power economy can also be attained because the vacuum side of the impeller does not have to work against boiler pressure or against devices requiring a high pressure to produce the vacuum. Furthermore, the boiler feed 25 side of the pump returns water only against the boiler pressure, and is not concerned with pumping air. The present arrangement also has the advantage of greater flexibility in its various operations and in its protection against loss of 30 priming and sealing water.

In Figure 17 there is illustrated an embodiment of my invention which employs an impeller which is the exact equivalent of the one used in the vacuum heating system just described and similar reference characters will be employed in 40 describing the various parts thereof. This impeller 70 is mounted on the end of the shaft 104 and is provided with the parts which comprise the centrifugal single fluid pump 72 on the left hand side thereof as seen in this figure. The multiple fluid suction pump side 80 of the impeller is provided with the propelling or aspirating fluid conduit 88 which leads to the short buckets 81 and the aspirated fluid enters the annular passage-way 89 through the holes 91 and is drawn through 45 the outer buckets 89 and thence through the mixing portion of the impeller and outwardly into the volute chamber of the casing.

The casing of this pump is indicated generally 55 by the reference character 201 and is preferably composed of the upper casting 202 and the lower casting 203, the latter being provided with the suitable base 204. The main inlet conduit 205 of the pump is preferably of the shape indicated, 60 the inlet opening being higher than the center intake passageways 11 of the rotary pump section 12. The main volute impeller chamber 207 is provided with the outlet 208 through which the fluid is centrifugally ejected. A priming water compartment 210 is provided on the right hand side of the pump and this compartment is always filled with priming water to a level indicated by the line $z-z$. The compartment 210 is provided with an air vent 212 which may serve to 65 exhaust entrapped air or gases to the atmosphere, or may be connected to a suitable container in case these gases are to be collected. The priming water in the chamber or compartment 210, is, of course, free to pass into the central conduit of the right hand side 80 of the

impeller and is also in communication with the volute chamber 214 of the right hand pump section. The priming water chamber 210 and the volute impeller chamber 214 are both sealed off from the intermediate aspirated fluid inlet chamber 215 by the sealing and bearing rings 216 and 217 fitted to suitable seating surfaces on the casing and the impeller. This inlet chamber is connected by means of the pipe 218 with the inlet conduit 205, the mouth of the pipe being 10 controlled by the float valve 219 occupying the chamber 220 in the wall of the conduit 205 which connects with the interior of the conduit by means of the narrow passageway 221.

The operation of this apparatus as a self- 15 priming pump will now be described, a body of priming water being also retained to the level $z-z$ by means of the elevated inlet conduit 205, even though leakage should occur around the clearances between the left hand pump section 20 70 and the right hand pump section 80. Thus the right hand portion of the pump is always primed and the priming water, being circulated continuously from the compartment 210 through the rotor or impeller through the volute chamber 214 and back to the chamber 210, acts as an 25 aspirating medium in drawing any air or gases which may be in the intake conduit 205 through the pipe 218, the chamber 215, the rotor of the pump 80 and thence into the priming water compartment 210 to escape through the opening 212. As the water level in the intake 205 rises due to the creation of a vacuum above this water level the left hand side 70 of the pump will receive 30 water and the continued rising of the water in 35 the inlet 205 will cause the float valve 219 to close the opening in the pipe 218 and prevent the by-passing of the water through this passageway and mingling with the priming water.

This arrangement can also be used as a suction 40 operated sewage ejector, for certain types of chemical pumps, for raising liquid containing entrained gases and in similar connections.

In Figure 18 of the drawings there is illustrated an arrangement in which either a single 45 suction or double suction pump such as described in the earlier portions of the present specification may be employed. This pump is indicated generally by the reference character 225, the aspirating medium admitted through the manifold 226 drawing the fluid through the pipe 227 controlled by the valve 228. The pump outlet conduit is indicated at 229. A separating tank 230 is provided which also constitutes a reservoir for the priming fluid. This fluid may be admitted from a suitable source through opening 232 controlled by the valve 233 which is actuated by the float 234, the outlet 235 of the tank being connected with the priming water manifold 226 of the pump. The outlet manifold 229 of the pump, through which the mixture of priming and aspirated fluids is ejected, is connected as at 237 with the upper portion of the tank 230 and the separated gaseous fluids pass off through the outlet 238 in the upper end of the tank and thence 50 through the conduit 239 to the point of utilization of such gaseous fluid. The splash plates or baffles 240 are provided in the tank over which the priming fluid flows to be recirculated. This pump can be employed to create vacuums beyond the 55 intake line 227 or may be employed to compress air or other gases in a container to which the outlet 239 may lead.

One of the uses to which this pump illustrated in Figure 18 may be put is that of providing the 60

necessary air pressure to operate a pneumatic sewage ejector, a portion of which is indicated generally by the reference numeral 250 in Figure 19. This ejector comprises essentially the tank or receiver 251 to which the sewer drain 252 from a building may be connected through the inlet check valve 253. A conduit 255 leads from the tank to the street sewer and is provided with an outlet check valve 256. The upper portion of the tank is provided with an air vent valve 257 and the necessary connections associated therewith. The numeral 260 indicates an extension of the air pressure pipe 239 leading from the pumping arrangement illustrated in Figure 18 and this pressure may be applied to the upper portion of the tank 251 by actuation of the valve 261.

A float 263 is provided within the tank 251 and is connected by means of the linkage 264 with an electrical switch 265, the contacts of which it is adapted to close in order to start the motor operating the pump 225 when the receiver 251 fills to a predetermined level. When the float switch is actuated, the pump 225 starts, compresses the air and delivers the air and the propelling water to the tank 230 wherein they are separated and the compressed air passed through the conduits 239 and 260 and the valve 261 to the sewage receiver 251 from whence the sewage is ejected through the check valve 256 and into the street sewer. The valves 228 and 261 may be electrically operated so as to open and close simultaneously with the starting and stopping of the pump 225 controlled by the float operated switch 265.

From the foregoing description, it will be seen that by means of my invention there have been provided several novel arrangements of pumping systems embodying the principles of my invention and certain other embodiments have been suggested herein. It will be understood that various changes and modifications may be made in the embodiments illustrated and described herein without departing from the scope of the invention as defined by the following claims.

As used in certain of the claims, the term "condensate fluids" is understood to be employed to designate not only the water of condensation of the steam, but also any air and uncondensed vapors which might be in the return main of the heating system.

Having thus described the invention, what is claimed as new and desired to be secured by Letters Patent is:

1. A centrifugal pump comprising, in combination, a casing enclosing an annular volute impeller chamber having a discharge opening at its periphery, a plurality of annular intake chambers spaced axially from said impeller chamber and from each other by bearing ring seats, a rotary impeller having radially extending vanes and shrouds disposed within said impeller chamber, said impeller being extended axially to form a tubular portion directed toward said intake chambers, bearing ring seats formed upon said impeller, and bearing rings between corresponding seats on the casing and the impeller, a partition dividing the radially extending portion of the impeller into two compartments and extended axially to correspondingly divide said tubular portion into annular conduits communicating respectively with the several intake chambers between the bearing rings.

2. A centrifugal aspiratory pump comprising, in combination, a casing having a centrally disposed radially enlarged volute impeller chamber,

and an axial extension in each direction therefrom, spaced annular chambers in said extensions providing intake chambers for propelled and propelling fluids, a rotary impeller having an axial hub and a centrally disposed radial enlargement comprising side shrouds and radial vanes connecting said shrouds to provide a plurality of fluid compartments, said shrouds being extended axially in each direction to form tubular impeller portions occupying the axial extensions of said chamber, a pair of partition members similar in configuration to said shrouds, having spaced radial portions intersecting said vanes and spaced from said shrouds, said partition members extending axially to form annular inlet conduits for propelling and propelled fluids respectively between themselves and said hub and said shrouds, said conduits being connected respectively with said intake chambers, the central radial portions of said partitions being of less extent than the corresponding portions of said shrouds whereby the propelling fluid admitted between the partitions will effectively aspirate the propelled fluid admitted between the respective partitions and side shrouds.

3. An impeller for centrifugal aspiratory pumps comprising, in combination, an axially elongated hub, radial vanes disposed around said hub at the central portion thereof, lateral shrouds connecting said vanes and extended axially of said impeller in each direction to form tubular impeller portions surrounding said hub, a tubular partition dividing each of said tubular impeller portions into inner and outer annular channels, said partitions flaring radially adjacent the center of said impeller, intersecting said vanes, and extending for a short distance between said laterally spaced shrouds to form with said vanes a series of nozzles for impelling fluid, said vanes and said shrouds providing a series of nozzles for the propelled fluid upon each side of said first named nozzles, and providing mixing jets outwardly beyond said partitions.

4. An impeller for centrifugal aspiratory pumps comprising, in combination, an axially elongated hub, radial vanes disposed around said hub, spaced lateral shrouds connecting said vanes, one of said shrouds extending axially of said impeller to form a tubular portion of said impeller surrounding said hub, a tubular partition dividing said tubular impeller portion into inner and outer annular channels, said partition flaring radially adjacent the vaned portion of said impeller, intersecting said vanes, and extending between said laterally spaced shrouds to form with said vanes a series of rotary nozzles for aspirating fluid, said vanes and shrouds providing a series of rotary nozzles for the aspirated fluid laterally of said first named nozzles, and providing mixing nozzles outwardly beyond the periphery of said partition.

5. An impeller for centrifugal aspiratory pumps comprising, in combination, an axially elongated hub, radial vanes disposed around said hub, spaced lateral shrouds connecting said vanes, one of said shrouds extending axially of said impeller to form a tubular portion of said impeller surrounding said hub, a tubular partition dividing said tubular impeller portion into inner and outer annular channels, said partition flaring radially adjacent the vaned portion of said impeller, intersecting said vanes, and extending between said laterally spaced shrouds to form with said vanes a series of rotary nozzles for aspirating fluid, said vanes and shrouds pro-

- viding a series of rotary nozzles for the aspirated fluid laterally of said first named nozzles, and providing mixing nozzles outwardly beyond the periphery of said partition, inlet openings in the laterally extended portion of said shroud for admitting the fluid to be aspirated to the outer one of said annular channels, and another opening in said impeller for admitting aspirating fluid to the inner one of said channels.
10. An impeller for centrifugal aspiratory pumps comprising, in combination, an axially elongated hub, radial vanes disposed around said hub, spaced lateral shrouds connecting said vanes, one of said shrouds extending axially of said impeller to form a tubular portion of said impeller surrounding said hub, a tubular partition dividing said tubular impeller portion into inner and outer annular channels, said partition flaring radially adjacent the vaned portion of said impeller, intersecting said vanes, and extending between said laterally spaced shrouds to form with said vanes a series of rotary nozzles for aspirating fluid, said vanes and shrouds providing a series of rotary nozzles for the aspirated fluid laterally of said first named nozzles, and providing mixing nozzles outwardly beyond the periphery of said partition, the outer ends of said axially extending shroud and of said partition merging together to seal the end of said outer annular channel, and inlet openings for admitting the aspirating and aspirated fluid to said channels.
7. An impeller for centrifugal aspiratory pumps comprising, in combination, an axially elongated hub, radial vanes disposed around said hub, spaced lateral shrouds connecting said vanes, one of said shrouds extending axially of said impeller to form a tubular portion of said impeller surrounding said hub, a tubular partition dividing said tubular impeller portion into inner and outer annular channels, said partition flaring radially adjacent the vaned portion of said impeller, intersecting said vanes, and extending between said laterally spaced shrouds to form with said vanes a series of rotary nozzles for aspirating fluid, said vanes and shrouds providing a series of rotary nozzles for the aspirated fluid laterally of said first named nozzles, and providing mixing nozzles outwardly beyond the periphery of said partition, the outer ends of said axially extending shroud and of said partition merging together to seal the end of said outer annular channel, inlet openings in the laterally extended shroud forming the tubular impeller portion for admitting the fluid to be aspirated into the outer one of said annular channels, and the inner one of said annular channels being opened at the outer end thereof to admit the aspirating fluid.
8. A centrifugal two-fluid aspiratory pump comprising, in combination, a casing enclosing a volute impeller chamber having a discharge opening at its periphery, a plurality of intake openings in said casing at points spaced axially from said impeller chamber, a rotary impeller comprising a plurality of radially extending vanes and axially spaced shrouds joining the side edges of said vanes and forming the side walls of the greater portion of said impeller, at least one of said shrouds being extended axially to form an elongated tubular portion directed to-

ward said intake openings, a partition conforming to the general configuration of said extended shroud, dividing the radially extending portion of said impeller into two compartments, and being extended axially and substantially coterminous with said shroud extension to correspondingly divide the tubular portion of said impeller into parallel concentric conduits, and sealed connections between said conduits and said respective intake openings.

9. A centrifugal aspiratory pump comprising, in combination, a casing having a centrally disposed radially enlarged volute impeller chamber, and an axial extension in each direction therefrom, intake openings through said casing leading into said axial chamber extensions for admission of the aspirating fluid and of the fluid to be aspirated, a rotary impeller having a centrally disposed radial enlargement comprising side shrouds and radial vanes connecting said shrouds to provide a plurality of fluid compartments, said shrouds being extended axially in each direction to form tubular impeller portions occupying the axial extensions of said chamber, a pair of partition members similar in general configuration to said shrouds and having axially spaced radial portions intersecting said vanes and spaced from said shrouds, said partition members extending axially within and substantially coterminous with the tubular portions of said shrouds to form parallel concentric inlet conduits for the aspirating fluid and the fluid to be aspirated respectively, said conduits being connected respectively with said intake openings at each end of said casing, the central radial portions of said partitions being of less extent than the corresponding portions of said shrouds, whereby the aspirating fluid admitted between the partitions will effectively aspirate the fluid admitted between the respective partitions and the side shrouds.

10. An impeller for centrifugal two-fluid aspirating pumps comprising, in combination, a substantially circular, central, radially enlarged portion and oppositely axially extending tubular portions, said central portion including a plurality of curved, substantially radially extending vanes and a pair of laterally spaced, somewhat convergent shrouds connecting the side edges of said vanes and each being extended axially in opposite directions to form the tubular extensions of the impeller, a tubular partition substantially coterminous with and dividing each of said tubular impeller portions into parallel, concentric conduits for the aspirating fluid and the fluid to be aspirated respectively, said partitions flaring radially adjacent the center of the impeller, intersecting said vanes, and extending between said laterally spaced shrouds to form with said vanes a series of rotary nozzles for the aspirating fluid, said vanes and the outwardly disposed shrouds providing a double series of nozzles for the aspirated fluid, one upon each side of the series of propelling fluid nozzles, the peripheral edges of said partitions terminating radially inwardly of the shrouds to provide mixing spaces outwardly of said aspirating nozzles, whereby the aspirating effect may take place wholly within said impeller.
